UNITED STATES PATENT OFFICE

2,075,163

SYNCHROSCOPE

Claude L. Bennett, Elgin, Ill., assignor of one-fourth to Eugene J. Hatch, Elgin, Ill.

Application September 6, 1932, Serial No. 631,947

8 Claims. (Cl. 88—14)

My invention relates to measuring instruments and particularly to measuring instruments employing principles of operation similar to those of the stroboscope, and an important object of my invention is to employ such principles of action in structure of new and novel form, for measuring the duration of and estimating the number of vibratory, rotary, or combination movements of elements which have a periodic or cyclic movement.

It is an important object of my invention to provide a machine or apparatus for measuring the duration distance and recurrence of such periodic or cyclic movements or portions thereof and to adapt such machine or apparatus to such work as the timing and checking of machines such as watches, clocks, and the like so as to enable accurately determining constants in the relationship between the distance covered and the time consumed in the movement of elements thereof, so as to enable adjusting such movements or reconstruction of the elements to move in the desired relationship to the constant which is the time-displacement ratio for the particular movement examined.

It is also an important object of my invention to provide an apparatus for carrying out the process described, wherein a periodically recurring visual element is postulated as the norm for comparison with an arbitrarily chosen moving element in the machine to be examined.

Other objects and advantages of my invention will be apparent from a reading of the following description in connection with the drawings wherein for purposes of illustration, I have shown preferred embodiments of my invention.

In the drawings:

Figure 1 is a transverse vertical section view through the watch or clock support.

Figure 2 is a side elevation view of Figure 1, taken from the right.

Figure 3 is a top plan view of the commutator structure.

Figure 4 is a vertical longitudinal section view through the commutator structure.

Figure 5 is a top plan view of Figure 1.

Figure 6 is a diagram of the relationship and electrical connections between the various elements of the embodiment.

Figure 7 is a perspective view of one of the commutator brushes.

Figure 8 is a view of a chart showing constants for the calculation of variations from accuracy of the movement of a watch balance-wheel,

Figure 9 is a bottom plan view of the brush carrier or rotor of the commutator structure shown in Figure 3.

Figure 10 is a horizontal sectional view showing in top plan the commutator.

Figure 11 is a transverse vertical sectional view taken through Figure 3 approximately on the line 11—11 and looking in the direction of the arrows.

Figure 12 is a transverse vertical sectional view through the brush carrier rotor and one of the brush holders showing the construction of one of the brush holders and the relation of the brush to the commutator.

Figure 13 is a top plan view of a modified form of commutator structure.

Figure 14 is a longitudinal vertical sectional view through a portion of 13.

Figure 15 is a similar sectional view through one of the individual spring contact holders shown in Figure 13.

Figure 16 is a top plan view of the post of one of said spring contact holders.

Since my invention comprises properly supporting the machine and the movement of a moving element which is to be measured and counted, such as a selected point on the balance wheel of a watch I provide the novel and efficient form of support illustrated in Figures 1 and 2 in the drawings, whereby the watch may be securely held and tested in any one of four or more positions, as it is the practice by manufacturers of high grade watches to do; and the synchronized commutator structure for producing the visual recurring means of comparison conveniently located within reach of the person making the test so that manipulation thereof may be done easily and conveniently while visually comparing the movement of the selected point on the balance wheel of the watch with the flashes of a special type of lamp such as a neon lamp.

The flashing of the lamp is controlled by adjustment of the commutator structure, which is driven by means of a synchronous prime mover, such as a synchronous electric motor.

The watch support comprises a table 57 which has depending sides which are traversed by bolts 59a which clamp friction producing concaved washers 59 against washers 60 and against the arms of a U-shaped bracket 55 which the bolts 59a also traverse, the bracket 55 being secured by means of a screw or bolt 51 so as to be rotatable with a dial 54 which is secured upon one face of a disk 53 said dial having numbers thereon at selected points 53a for enabling proper designation of the positions which the table 57 and con-

5

50

55

sequently the watch secured thereon are made to assume while the tests are being conducted in the different positions; and the disk 53 is secured to a suitable support by means of a bracket 49.

Below the table 51 I mount a base 65 which has U-shaped arms traversed by a bolt 61 which also traverses arms 64 which are disposed between the arms of the bracket 65 and secured to the mirror 63. A washer 67 and a thumb nut 62 disposed on one end of the bolt 61 provide means for tightening the mirror 63 against rocking on the bolt 61 and in any desired adjusted position. The mirror 63 is provided for reflecting into the line of vision of the operator the movements of the selected point on the balance wheel of the watch, when the watch is in an inverted position such as that indicated at 68 in Figure 2. The table 51 is provided with a suitable spring or friction receptacle 58 which enables securing of a watch upon the table in a variety of positions in the plane of the table.

The preferred form of commutator structure is clearly illustrated in Figure 4, wherein the letter T generally designates a suitable table or platform which is provided at longitudinally spaced points with longitudinal slots 24 and 25. In the slot 24 is placed a shaft 24a on the lower end of which is a washer 28 engaging the bottom of the table T and spanning the opening 24, a wear washer 29 thereunder and a nut 30 for drawing a portion of larger diameter 27 into engagement with the upper surface of the table in cooperation with the washer 28 which engages the under-surface of the table, thereby enabling adjusting and locking the shaft 24a at any point of the length of the slot 24. Rotatably supported on the shaft above and by the portion 27 is a toothed wheel or pinion 5 and similarly disposed on the shaft above the pinion 5 is a flywheel governor or balancer 26 which is pinned to the pinion 5 by the screw 26a which traverses the pinion 5 and passes upwardly into the flywheel 26 as shown in Figure 4.

Below the table T which is suitably supported, 45 is a synchronous electric motor shown in Figure 4, whose shaft 2 rises through an opening in the table T and thereabove and has on its upper end a nut 31 and the washer 32 clamping thereto a large gear 3 which is meshed with the pinion 5 and also with the commutator pinion 4.

The commutator pinion 4 is mounted on the enlarged lower end portion of a shaft 15 which is mounted in a slide block 22 which rests upon the table T and has depending bolts 22b passing 55 through the slot 25 and engaged with a plate 22a which engages the underside of the table T. Manipulation of the bolts 22b enables clamping of the block 22 in the desired position in the slot 25. The adjustability of the shaft 24a carrying 60 the governor 26 and of the block 22 enables accommodation to be made for different sizes of pinions and gears, when the apparatus is used in connection with different periods and cycles.

65 Mounted upon the commutator gear 4 is a commutator rotor 6 which comprises a disk having mounted thereon a broken ring 7 of dielectric material in the radial opening 7a of which, as illustrated in Figure 10 and Figure 4 is placed an electrically conductive element 21. As shown, the commutator plate 6 is fastened with screws to the commutator gear 4.

Mounted on the upper and reduced portion of the shaft 15 is the brush carrier or rotor 9 which 70 comprises a dielectric disk having a central open-

ing receiving the reduced lower end portion of a knurled dielectric knob 12, the disk being fastened with screws to the knob as shown. For normally urging the brush carrier toward the commutator there is provided surrounding the 5 reduced upper end portion of the shaft 15 a helical spring 16 which is downwardly pressed by a washer 13 held in position by a split nut 14 which is adjustably anchored to the shaft 15. The spring 16 is located in a recess in the upper 10 part of the knurled knob 12 as shown in Figure 4.

Arranged within the periphery of the brush carrier rotor 9 and circumferentially spaced are brush holders 11 which are numbered 1' to 8' in the drawings, Figure 3. Each of the brush holders 11 comprises a bolt which passes upwardly through the brush carrier rotor 9 and has a notched head on its lower end which receives and holds a U-shaped brush wiper 8 illustrated in Figure 7. The upper end of the bolt is threaded 20 and has threaded thereon a washer 10 and a knurled clamping nut 11a illustrated in Figure 12. The brushes 8 are held in contact with the upper side of the broken ring 7 as indicated in the drawings.

For preventing rotation of the disk 9 which would otherwise occur because of the rubbing of the commutator ring 7 and segment 21 against the brushes 8 I provide a brake structure which includes the standard 18 which is mounted upon the block 22 and a longitudinally movable rod 19 which traverses the standard 18 and is provided on its outward end with a handle 20. An enlarged squared head or brake shoe 18a is on the inward end of the rod 19 and slides in a conformably shaped recess in the standard 18 wherein a coiled spring circumscribed on the rod 19 acts between the inner end of the recess and the head or brake shoe 18a for pressing the brake shoe against the outer edge of the brush carrier or rotor 9. It 40 will be obvious that the brake 18a is provided to prevent the rotation of the brush carrier or rotor 9 by the revolving commutator ring 7 and segment 21 until it becomes desirable to advance or retard the occurrence of the contact of the 45 brushes 8 with the commutator segment 21 for the purpose of changing the incidence of the flashes with which the movements of the selected point on the balance wheel of the watch are to be 50 visually compared.

Contact of the brushes 8 with the segment 21 of the commutator and hence the occurrence of the flashes of the neon lamp is so adjusted by the means described as to be in step with the correct standard time swing for the balance arm of the watch, clock, or other periodically revolving or reciprocating object which is being tested so as to enable observing whether or not the object is moving at the correct speed and beat period. The brushes 8 and the commutator segment 21 60 are arranged to close an electrical circuit and cause the neon glow lamp, or an electric light to flash, also a relay for operating a counter or other apparatus requiring more current to operate than is needed for the operation of the lamp.

The duration of contact must not exceed the time it takes an accurately swinging balance arm or pendulum indicator or any other observation indicator which may be selected, to move an 70 amount equal to the width of the selected detection unit, such as the width at the out end of the balance arm, but can be less so that when the commutator segment 21 closes and breaks the circuit the neon light, electric light, and relay will 75

be energized and deenergized in a period of time that will enable a clear observation of the detection unit or balance arm. This detection unit or balance arm will appear as stationary or as 5 shifted according to its position while in motion and during the standard for periodical contacts of the brush 8 with the segment 21.

In a case of testing the speed of movement of other than revolving or reciprocating objects the 10 closing of the circuit is arranged to take place at equal intervals of time so that the observation indicator on the moving object will show itself according to its velocity at a location proportional to the standard amount of movement when compared with the time duration of the test.

It is arranged that the object being tested will move in the same direction each time the circuit is closed by the commutator segment, except when a rearrangement is made in which closing of the 20 circuit will occur for each direction of reciprocating motion. The latter arrangement is desirable when testing to locate the halfway point on the stroke and also for locating the end of the strokes, thereby making it possible to determine 25 accurately the length of the swing and the end of the swing as well as the halfway location of the balance motion on a watch or pendulum or any other object having reciprocatory motion.

This is done by advancing or retarding the 30 closings of the circuit so that the neon light is energized and flashes at a time when the balance arm or any other observation indicator appears stationary and clear with no apparent wavering which would appear at any other energization of 35 the neon light. It is also possible to determine the end of the stroke of the observation indicator by causing the neon light to be flashed at a slightly faster or slower speed than that of the balance arm or pendulum. By this procedure a 40 slowly shifting appearance of the balance arm or pendulum can be obtained in which the arm or pendulum appears to move toward one end of its stroke and then reverse itself and proceed slowly toward the opposite end of the stroke.

In the case of a watch, clock, or any other object with a balance arm, pendulum, or any other reciprocating or revolving object, it is advantageous to cause the neon light to flash at equal intervals of time so that the observation indicators 50 on the moving objects will appear at approximately the same location while the object is moving in one direction only.

If the light flashes for each stroke go and come, 55 the observed indicator will have a wavering appearance when the moving object under observation has a speed differing from that of the commutator and the neon light flashes which are considered standard.

One advantage of arranging a closing of the 60 light circuit at every other stroke rather than at every stroke is that a uniform reading appears even if the object under test is moving at a speed differing some from that of the standard. This 65 enables comparison of my detection unit with any number of like units of which the observation indicator shows or can be estimated to have drifted to the right or to the left, whereby I compare the number of these units off in a standard unit of time.

By reason of the uniformity of reciprocating motion on watch balances a table, Figure 8, is 70 calculated out so as to show the number of seconds off as accumulated in a twenty-four hour period. The table being calculated on the basis

of a comparison of a unit of displacement within a unit of time, thereby making it possible to measure the velocity in various units of measure.

The effect of the weighted flywheel governor 26 which is attached to the pinion 5 and receives its motion from gear 3 is to impart steadier and smoother running to the commutator segment 21.

The slots 24 and 25 in the table supporting the 10 commutator mechanism and the governor enable adjusting the gears and substitution of gears which are required to drive the commutator at the speed desired.

The commutator brake 18a is arranged to hold 15 the commutator brush carrier 9 and brushes 8 stationary so that the synchroscope reading can accumulate. The brake may be released temporarily from engagement with the brush carrier or rotor 9 to enable turning the rotor 9 by means of the knurled knob 12 in order to advance or retard the engagement of the brushes 8 with the 20 commutator segment 21, thus enabling a person to tell if the swing or stroke which said person is watching is coming from the right or from the left hand direction. This is accomplished by noticing the direction of the drift of the observation indicator on the object under test and then comparing the direction in which the commutator is revolving with the direction in which the brush carrier or rotor 9 was turned by hand, and the 25 direction in which the observation indicator appears to have shifted. By means of the described manipulation it is also possible to tell if the object under test is running faster or slower than the standard speed, by noticing whether the observation indicator appears sooner or later in its swing.

The adjustable brush carrier or rotor 9 and the brushes are insulated from each other and so placed that in the event of either an advance 40 or a retard adjustment of the rotor 9 for the purpose of closing the circuit to energize the neon light and a relay earlier or later than normal, that a better location for watching the observation indicator can be obtained and that it may be readily determined which way the swing of the 45 balance arm or any other reciprocating member having an observation indicator, may be moving. This adjustable brush carrier or rotor 9 will enable a person to tell if the moving object under test is running fast or slow, by comparing the 50 directions of rotation of the commutator segment 21 with the direction of drift of the observation indicator. If the commutator is rotating clockwise and the observation indicator on the moving object under test is observed to drift toward the 55 right or clockwise, then by turning the knob 12 toward the right or clockwise the balance arm or any other observation indicator is caused to appear farther to the right of its originally observed position, then the apparent running drift of the observation indicator to the right indicates the object is running fast because it is gaining on the direction of stroke. If the rotor 9 is turned toward the left or counterclockwise, then 60 the light will flash sooner than normal and the observation indicator will appear as shifted toward the left of the originally observed position, thereby indicating that the observation indicator on the moving object will be observed at constant 65 intervals of time moving toward the right.

By using either of the foregoing procedures the observer can tell the direction of motion of the object under test and can determine if the object is moving faster or slower than the standard 70

velocity. For example, if the object being tested is found drifting slowly clockwise or toward the right and the commutator 21 is rotating clockwise and in the direction of movement of the observation indicator, it proves that the observation indicator is moving faster than the commutator cycle and the period of light flashes which is the indicator of the standard by which the movement of the observation indicator is being compared. If in the foregoing test the direction of drift of the observation indicator has appeared to be toward the left instead of toward the right, it would have indicated that the object was moving slower than the commutator cycle, and hence slower than the standard velocity. The relay operated counter 46 is provided to record the number of circuit closings taking place during the tests. The balance arm on most watches swings in one direction $2\frac{1}{2}$ times per second or 150 times per minute. Therefore, at the end of 150 counts on the counter it is necessary to estimate the distance that the balance arm drifted during the test. From this it is possible by reference to a table, such as that shown in Figure 8, to tell how close in seconds of standard time or any other units of measure, by which the balance arm of the watch or of any other revolving or reciprocating object which may be running with respect to the standard 24 hours of time. A table can be made to show the results in seconds per day, revolutions per minute, or in any other suitable units of measure.

The binding nut 14 is located on shaft 15 and is for adjusting the spring 16 so as to press the commutator brushes 8 against the commutator disk 7 so that the commutator may run as smoothly as possible and make a good contact for closing the light circuit.

The multiple point switch 39 has its points connected with brush holders 1' through 8' so that by selective setting of the switch 39 which may be located at a remote place from the commutator and motor, any desired adjustment of the incidence of the closing of the circuit to energize the neon light earlier or later with respect to the position of the observation indicator on the object being tested may be made.

It is hereby possible to achieve at a distance from the commutator an effect which is similar to that obtainable by manually adjusting the disk 9 by means of the knob 12. This adjustment of the incidence of the closing of the circuit is desirable to cause the light to flash at a preferred position and at a time in which the observation indicator of the object may be viewed, and also to enable determining the direction of the stroke of the object under observation, and to assist in determining whether the movement of the object under observation is faster or slower than the standard cycle period.

In testing a watch to determine its time keeping qualities, the watch is placed in the adapter 58. The adapter 58 is mounted on the adjustable table 57 which is held between the two arms of the bracket 55, which in turn, is held firmly attached to the large dial 54. The dial 54 and the bracket 55 are mounted on the bolt 51 which is drawn up against the bracket 49, washer 48a and the spring friction washer 48 so that the dial 54 and the bracket 55 along with the adjustable table 57 and the watch adapter 58 can be turned on bolt 51 with some friction so that the dial 54 and the watch can be set at the desired angles at which the time keeping ability of the watch or

clock or other time escapement is tested at for position timing.

The adjustable table 57 enables the watch to be tested with the back of the watch up as shown in the top view at 56 also the table 57 can be turned completely over so that the watch can be timed with the back side of the watch down as indicated at 58. To test a watch or an escapement in the various perpendicular positions it is necessary to set the adjustable table 57 in the position shown at 57a with the flat side of the table and the back side of the watch facing the front. For testing a watch or an escapement in the front perpendicular and the various right and left angular positions, the fixture and dial is turned to 15 the position desired.

The adjustable plain mirror or the magnifying mirror 63 is set facing the back side of the watch or other reciprocating escapement to enable the operator to view the back side down of the watch, especially the balance arm and its action while the test is being made according to the synchroscope and stroboscope principles. The numerals 53a on the dial are provided as aids in showing the positions at which the watch or other object 25 is mounted upon the adjustable fixture while being tested. Each position or setting is given a number for record purposes until the watch is finally passed as running on time in every one of these positions.

When using a constant frequency controlled alternating current such as 60 cycle current through the commutator to light the neon light, the duration of the contact should be less than the time frequency of the alternating current used, so that when the motor is running at the constant predetermined speed the neon light will flash only on one of its poles and continue to flash on the same pole as long as the speed of the motor does not change. I have used about 1/500 of a 40 second for the duration of contact.

It is possible to tell whether the motor is driving the commutator at the desired speed by watching the light flash appear on the same pole in the neon or other gas ionizing tube for a period of time. The above holds true for all of the A.C. polarity alternations which happen to be in multiple of the frequency of contact of the commutator.

The relay 45 is operated in the circuit with the neon light, its purpose is to control another circuit suitable for operating the mechanical or magnetic counter 46. The purpose of the counter is to serve as a check on the duration of the tests so that the length or the proportional amount of drift of the observation indicator when viewed by the aid of the constant periodic flash of the neon or other light, which is focused on the object under test in a dark or semi-dark place, can be compared with the duration of time it takes in drifting.

The fact that the commutator which controls the neon light and the relay is run with the synchronous motor, insures the constant periodic 65 flashing of the neon light and operation of the counter in exact step with the neon light and the relay. One arrangement is to have the counter register a predetermined number of light flashes per minute.

In place of using the relay in the circuit with the neon or other form of light flashes to operate the counter it is possible to use a direct cam. The counter may be thrown in by a clutch which is not shown, when the test is to begin and thrown 75

out when desired or when a predetermined stopping point is arrived at where an electric contact can cause a signal light or a bell which is not shown to operate. In the case of the cam operated electric contact or the commutator contact it is only necessary to throw a switch on or off in the contact circuit to start or stop the counter.

An observation housing may be built to house the moving object under test in such a way as to adequately prevent most of the outside light from entering and neutralizing the effect of the neon light flashes on the object under test. Openings in the housing may be placed at a distance from the object to be tested so as to enable viewing the object under test and from different points of vantage.

Besides the adjustment for retard or advance of the incidence of the circuit closings which is available through manually rotating the rotor or brush holder 9, the individual brushes may be given angularities with respect to the radii of the brush holder rotor 9 and the commutator segment 21 so that by using the switch 40 the proper brush may be chosen to engage with the segment 21 sooner or later.

The double pole double throw switch 71 provides a means for choosing either the direct current or an alternating current for operating the neon tube or glow lamp through the commutator circuit.

An example of a watch timing calculation using my "synchroscope": The inside dia. of the balance rim of the balance wheel in a watch equals .40".

The average one way swing or travel of the balance arm equals

$$\frac{11}{16}$$

40 of a revolution. The detection unit of drift equals .04" and is the unit of motion based on the exact distance through which the balance arm at the outer end should travel in 24 hours of motion.

45 3. 1416

.40" = the inside dia. of the balance rim.

$$1256640$$

$$\frac{.6875}{16} = \frac{11}{16}$$

$$6283200$$

$$8796480$$

$$10053120$$

$$7539840$$

55 .04(8639400000 = $\frac{11}{16}$ (of the circumference of the .40" dia. or 1 swing)

21, 5985 = units per swing

5 swings per second of the balance arm.

60 107. 9925 units per second

$$\frac{60}{60}$$

6479. 55 units per minute (carry forward and multiply by 60)

$$\frac{60}{60}$$

65 388773. 00 units per hour

$$\frac{24}{24}$$

1555092
777546

70 9330552 units in 24 hours

If one detection unit equals .04" movement of the balance arm at the outer end of same and for any other observation indicator, that would indicate the 1/9,330,552 part of 24 hours, or

the 1/6480th part of a minute or the 1/108th part of a second.

6480)9,330,552 (1439.9 say 1440 units or 1 unit for 6480 each minute in 24 hours.

$$\frac{28505}{25920}$$

$$\frac{25855}{19440}$$

$$\frac{64150}{58320}$$

$$58320$$

5

10

15

20

25

108)1440(13.33 = seconds off in a 24-hour run. The 108 synchroscope showing a 1 unit of drift in 1 minute.

$$\frac{360}{324}$$

$$\frac{360}{324}$$

$$\frac{360}{324}$$

30

35

If the synchroscope shows only 1 unit of drift after the 10 minutes of test, that would indicate: $13.33 \div 10 = 1.333$ seconds off in a 24 hour run.

Thus a table similar to the one shown in Figure 8, can be made to show the amount in seconds off from the standard for any duration of a test.

There are $2\frac{1}{2}$ swings in the same direction per second or 5 swings counting both of the directions per second.

One second = 108 Det. units.

One detection unit of .04" drift for each minute in the 24 hours.

50 Detection units in each sec. = $\frac{1440}{108} = \left\{ \begin{array}{l} 13.33 \text{ sec. off in} \\ \text{the 24 hour run} \\ \text{if the synchro-} \\ \text{scope shows 1} \\ \text{unit off in a 1} \\ \text{min. test.} \end{array} \right.$

55 The table in Figure 8 is for use in conjunction with my synchroscope for the timing of revolving and reciprocating motions. Most of the watches have a balance arm swing of approximately 1 revolution each way, or $1\frac{1}{3}$ rev. per cycle.

If the watch has a swing of $\frac{1}{8}$ to $\frac{1}{16}$ rev. more or less it will not change the reading on the table shown in Figure 8, a great deal. I have tested watches that ran with accuracy within $\frac{1}{2}$ second a day and which had a .40" inside dia. of the balance rim or at the position of the observation indicator, and will say that it took about 20 minutes to notice a drift of the balance arm or the observation indicator of .04", thus by reference to the table Figure 8 it shows that the watch was running within $\frac{1}{2}$ second of accuracy

in what would be equivalent to 24 hours of continuous running.

For determining "fast" or "slow", and the exact frequency of the swing of the balance of any escapement controlled by a regular proceed as follows:

Cause the neon light or other light means to flash at the desired standard intervals of time upon a revolving or reciprocating object such as 10 a balance arm and ring, so that the observation indicator on the balance arm, ring, pendulum or other moving object may be observed in a dark or semi-dark place with the observation indicator moving in the same direction for each standard 15 flash.

This offers the preferable method of telling the fast or slow and will aid in correcting the time motions of the observation indicator on the balance arm, ring, and hair spring of a watch or 20 clock or on any other reciprocating escapement that has the regulator arm or an adjustable means for controlling the balance and the hair-spring reciprocating periods.

After noticing the position of the observation 25 indicator on the balance or pendulum while under test in my synchroscope machine, the regulator of the watch or the like is moved in the fast or the slow direction which is marked or known on the watches and clocks and similarly regulated 30 escapements. A sudden shift of the observation indicator, the balance run or the pendulum will be noticed. If the regulator is moved to the "fast" or the "slow" and after having previously noticed the gradual drifting direction of the observation 35 indicator the balance arm or the pendulum, it can be seen that if both of the motions, the direction of the error drift of the balance arm or other observation indicator and the direction of the sudden shift of the observation indicator 40 was caused by moving the regulator, and took place in the same direction, as the motion which is being tested and is therefore indicated as fast or slow according to whether or not the regulator was moved to the "fast" or the "slow".

45 It is possible to shift the regulator of the watch or the like to a position in which the balance arm or a pendulum, while in motion under the synchroscope flashes will apparently appear at a standstill for a minute or more according to the 50 accuracy of same. The degree of accuracy can be determined by comparing the amount of drift in units of the observation indicator in a definite duration of test thus indicating the amount of error in units for the length of time tested and 55 by referring to the table Figure 8, the operator is enabled to ascertain the amount in seconds that watch will run off in 24 hours. This information will enable a watch expert to intelligently adjust the balance hair spring or any of the 60 other time controlling parts which are in the watch or clock or in any other escapement so as to permit the regulator to be set at the central or the intermediate position, which is half way between the "fast" and the "slow" or at any other 65 desired location. With my device it is possible to check the extreme accuracy required of moving and reciprocating objects by the Bureau of Standards at Washington, D. C. and for others elsewhere.

70 In Figure 13 is shown an alternative form of the commutator structure, which, instead of the brush rotor 9 and its appurtenances, is provided with a stationary table in the form of a plate 100 which is rigidly mounted by blocks 101 traversed 75 by bolts or the like 102 to the table 103. The

table 103 has mounted therein the shaft 104 which has a portion of larger diameter 105 resting against the upper surface of the table 103 and cooperating with a washer 106 which is urged by a screw 107 into engagement with the under face of the table 103. In this embodiment of the invention the brushes or contact elements are stationary, whereas in the embodiment described above, the contacts or brushes are of the rotary type, that is they are carried so as to be 10 capable of being manually rotated relative to the commutator. In the embodiment now being described the shaft 104 carries the pinion 108 which corresponds in action and function and position to the pinion 4, of the first described embodiment of the invention. The pinion 108 rotates relative to the shaft 104, and carries around the shaft a drum type commutator 109 which comprises a cylindrical block 110 of insulating material and a metallic contact portion 111. 15

20 Mounted in the table 100 and surrounding the commutator 109 is a plurality of spring contact holders 112 corresponding in position and number to the brush holders 11 of the first described embodiment of the invention. Each of the spring contact holders 112 comprises a bolt 113 which is slotted as indicated at 114 from its upper end. The bolt passes through the table 100. A threaded bushing 115 is engaged on the bolt 113 above and in engagement with the upper surface of the table, while a nut 116 and a lock nut 117 are on the lower end of the nut below and engaging the undersurface of the table for clamping the bolt in adjusted position.

25 Threaded upon the upper end of the bolt 113 is a knurled clamping knob 118 which clamps a spring rod 119 located in the slot 114 against the upper end portion of the bushing 115 for clamping the spring contact rod in the desired 30 position of adjustment. The radially inward 35 end portions of the spring contact rods 119 are deflected as shown in Figure 13 and are engaged with the commutator 109 in an evident manner.

The pinion 108 is driven by a large intermediate gear corresponding to the gear 3 of the first 40 described embodiment, and the large intermediate gear is driven by virtue of its mounting upon the shaft of the prime mover of synchronous type, and the large intermediate gear is also in mesh 45 with the pinion which carries the flywheel for regulating and smoothing the operation of the 50 gears and consequently of the commutator, thereby assuring uniform rotation thereof.

55 Although I have shown and described herein preferred embodiments of the invention, it is to be definitely understood that I do not desire to limit the application of the invention thereto, and any change or changes may be made in material and structure and arrangement of parts, within the spirit of the invention and the scope of the 60 subjoined claims.

What is claimed is:—

1. An apparatus for testing the time-displacement of a selected point on the balance wheel or other periodically or cyclically moving part of a 65 watch or the like, said apparatus comprising a support, a synchronous prime mover mounted in conjunction with the support, flywheel governor means on the support, commutator means on the support, a mutual connection between the synchronous prime mover and the flywheel governor and the commutator means, whereby the commutator means is driven at a uniform predetermined rate, a rotatable brush rotor, a plurality of circumferentially spaced brushes carried by 70

the rotor for contact with the commutator, and 5
brake means carried by the support for engagement
with the brush rotor for preventing rotation
of the rotor by the commutator, whereby
5 to retain said brush rotor in a position of rotation
in which the incidence of the brushes with
respect to the electrical circuit completing means
carried by the commutator is either retarded or
advanced.

10 2. An apparatus for testing the time-displacement
of a selected point on the balance wheel
or other periodically or cyclically moving part
of a watch or the like, said apparatus comprising
15 a support, a synchronous prime mover mounted
in conjunction with the support, flywheel gover-
nor means on the support, commutator means
on the support, a mutual connection between the
synchronous prime mover and the flywheel gov-
20 ernor and the commutator means, whereby the
commutator means is driven at a uniform pre-
determined rate, a rotatable brush rotor, a plu-
rality of circumferentially spaced brushes car-
ried by the rotor for contact with the commu-
25 tator, brake means carried by the support for
engagement with the brush rotor for preventing
rotation of the brush rotor by the commutator
whereby to retain said brush rotor in a position
of rotation in which the incidence of the brushes
30 with the electrical circuit completing means car-
ried by the commutator is either retarded or
advanced, an electric circuit having conductors
connected individually to said brushes, a multi-
ple switch connected to said conductors, relay
35 means and incidence counting means connected
to the arm of said switch, and electrical light
means having one side connected to said relay
means, the remaining side of said electrical light
means being connected to a power circuit in
40 which said synchronous prime mover is con-
nected, said power circuit being also connected
to the electrical connection element of the com-
mutator, whereby operation of said electrical
light means is synchronized with the rotation
45 of the prime mover, so as to establish a visual
norm in the form of periodic flashes for visual
comparison with the incidence of the selected
point on the balance wheel or other moving part
of the watch or the like.

3. An apparatus for testing the time-displacement
50 of a selected point on the balance wheel
or other periodically or cyclically moving part of
a watch or the like, said apparatus comprising
a support, a synchronous prime mover mounted
in conjunction with the support, flywheel gov-
55 ernor means on the support, commutator means
on the support, a mutual connection between the
synchronous prime mover and the flywheel gov-
ernor and the commutator means, whereby the
commutator means is driven at a uniform pre-
60 determined rate, a rotatably adjustable brush
rotor, a plurality of circumferentially spaced
brushes carried by the rotor for contact with the
commutator, brake means carried by the support
for engagement with the brush rotor to prevent
65 the same from being rotated by the commutator,
so as to cause said brush rotor to hold a retarded
or advanced adjustment of the incidence of the
brushes with the electrical circuit completing
means carried by the commutator, an electric
70 circuit having conductors connected individually
to said brushes, a multiple switch connected to
said conductors, relay means and incidence
counting means connected to the arm of said
switch, electrical light means having one side
75 connected to said relay means, the remaining

side of said electrical light means being connected
to a power circuit in which said synchronous
prime mover is connected, said power circuit be-
ing also connected to the electrical connection
element of the commutator, whereby operation
5 of said electric light means is synchronized with
the rotation of the prime mover, so as to establish
a visual norm in the form of periodic flashes for
visual comparison with the incidence of the se-
lected point on the balance wheel or other moving
10 part of a watch or the like, and manual means
for adjusting the brush rotor so as to advance
or retard the rotor with respect to the rotation
of the commutator, whereby to advance or retard
the flashes with respect to the incidences of the
15 movement of the selected point of the watch
balance wheel, so as to enable visually determin-
ing whether the balance wheel movement is lag-
ging behind or is advancing ahead of the flashes
of the light means indicating the norm of the
20 movement for the balance wheel.

4. An apparatus of the character described
comprising a synchronous motor, a rotatable
commutator driven thereby including contact
segment means, a rotatably adjustable brush
holder having a plurality of equally circum-
25 ferentially spaced brushes thereon, said brush
holder being supported so that the circle of said
brushes is concentric with the axis of said com-
mutator and said brushes may engage said seg-
ment means when said commutator is rotated
30 by said motor relative to said brush holder, and
releasable brake means supported adjacent to
said brush holder and normally engaging said
brush holder and preventing said brush holder
35 from being rotated by reason of the engagement
of its brushes with said rotatable commutator,
the engagement of said brake normally prevent-
ing rotation of said brush holder in either direc-
tion from an adjusted position.

5. An apparatus of the character described
comprising a synchronous motor, a rotatable
commutator driven thereby including contact
segment means, a rotatably adjustable brush
holder having a plurality of equally circum-
45 ferentially spaced brushes thereon, said brush
holder being supported so that the circle of said
brushes is concentric with the axis of said com-
mutator and said brushes may engage said seg-
ment means when said commutator is rotated by
50 said motor relative to said brush holder, and
releasable brake means supported adjacent to said
brush holder and normally engaging said brush
holder and preventing said brush holder from
being rotated by reason of the engagement of its
55 brushes with said rotatable commutator, the en-
gagement of said brake normally preventing
rotation of said brush holder in either direction
from an adjusted position, each of said brushes
being normally aligned with a diameter of said
60 brush holder and adjustable to engage and leave
said segment means at different angles.

6. An apparatus of the character described
comprising a synchronous motor, a rotatable
commutator driven thereby including contact
segment means, a rotatably adjustable brush
holder having a plurality of equally circum-
65 ferentially spaced brushes thereon, said brush
holder being supported so that the circle of said
brushes is concentric with the axis of said com-
mutator and said brushes may engage said seg-
ment means when said commutator is rotated by
70 said motor relative to said brush holder, and
releasable brake means supported adjacent to
said brush holder and normally engaging said
75

brush holder and preventing said brush holder from being rotated by reason of the engagement of its brushes with said rotatable commutator, the engagement of said brake normally preventing rotation of said brush holder in either direction from an adjusted position, and manual means for rotatably adjusting said brush rotor relative to said commutator.

7. An apparatus of the character described comprising a synchronous motor, a rotatable commutator driven thereby including contact segment means, a rotatably adjustable brush holder having a plurality of equally circumferentially spaced brushes thereon, said brush holder being supported so that the circle of said brushes is concentric with the axis of said commutator and said brushes may engage said segment means when said commutator is rotated by said motor relative to said brush holder, and releasable brake means supported adjacent to said brush holder and normally engaging said brush holder and preventing said brush holder from being rotated by reason of the engagement of its brushes with said rotatable commutator, the engagement of said brake normally preventing rotation of said brush holder in either direction from an adjusted position, and an electrical circuit including said motor, said brushes, a lamp, and remote switch means having a multiplicity of points to each one of which one of said brushes is connected, said switch being operable to predetermine retarded, advanced, or coincident incidence of the energization of the said lamp by engagement of said brushes with said segment means.

8. An apparatus of the character described comprising a synchronous motor, a rotatable commutator driven thereby including contact segment means, a rotatably adjustable brush holder having a plurality of equally circumferentially spaced brushes thereon, said brush holder being supported so that the circle of said brushes is concentric with the axis of said commutator and said brushes may engage said segment means when said commutator is rotated by said motor relative to said brush holder, and releasable brake means supported adjacent to said brush holder and normally engaging said brush holder and preventing said brush holder from being rotated by reason of the engagement of its brushes with said rotatable commutator, the engagement of said brake normally preventing rotation of said brush holder in either direction from an adjusted position, and an electrical circuit including said motor, said brushes, a lamp, and remote switch means having a multiplicity of points to each one of which one of said brushes is connected, said switch being operable to predetermine retarded, advanced, or coincident incidence of the energization of the said lamp by engagement of said brushes with said segment means, said remote switch means including a plurality of remote individual lamps selectively connectible to said remote switch means by second individual switch means for energization by the engagement of said brushes with said segment means.

CLAUDE L. BENNETT. 35
